EARTHEN PIT SHORING MEANS

John L. Washbourne, Douglaston, Long Island,
N. Y.

Application April 18, 1939, Serial No. 268,461

14 Claims. (Cl. 61—41)

The present invention relates to an improvement in sheathing for retaining and shoring the earthen walls of pits, or preferably open earth cuts, dry wells, and sumps, or intrenching, wherein in vertical earth cuts are prevented from caving in, during excavation. This type of construction is known as pit sheeting.

The present construction may be utilized in such a manner as to be erected, concurrently with the digging of the excavation, to follow the deepening excavation to the bottom thereof, as such excavation proceeds, and may be likened to the method of the follow up system of tunneling cutting shields or headings wherein the lining rings are laid as the cutting shield progresses.

The essential difference in the present construction is that the present construction is of simple, metal channel beam construction, is made, preferably of horizontal arrangement of component parts, is assembled, as required, as the excavation proceeds, and at the bottom thereof, and at all times provides an interior, vertical earth wall sustaining means all round within the walls of the pit or trench being dug.

The present construction is so developed, that it may be removed if desired, or it may be left in situ, and reinforced by a concrete lining, which, owing to the construction of the sheathing elements, may be perfectly keyed or bonded thereto, as will hereinafter appear, later, as outlined in detail.

In the present construction, the horizontal reinforcing beams may be alternating wide and narrow, and are affixed to one another at their adjacent edges, thus to form a complete crib, each beam acting as a strut, without any reinforcing elements other than the shoring beams themselves and the essential attaching elements, such as bolts and spacers, thus creating a rigid rectangular framework or crib.

One of the features of advantage is that in excavating long trenches, a series of the shoring units may be placed side by side, or end to end, as desired, and afterwards removed, as desired.

The present construction may also, by providing roofing and flooring elements, be used in the construction of vaults, for permanent construction.

In one form of the system of sheeting disclosed herein, spaces may be left between the shoring elements thereof for economy of material, inspection of earth, tamping, when required, soil inspection and water drainage.

A further feature of advantage, in addition to 55

the foregoing noted advantages of the present method of construction is that the crib may be made up of light gauge metal units, may be erected piece-meal without undue disturbance or loosening of the earth walls, and will solidly retain the said walls during the progress of the excavation and thereafter.

The use of extraneous cross and corner braces and gussets are eliminated in the present construction, and where the construction is removed after its primary use, the elements of the structure may be used over and over again.

The foregoing, and other features of advantage, will be apprehended, as the herein description 10 proceeds, and it will be obvious that modifications may be made in the structure herein disclosed without departing from the spirit hereof or the scope of the appended claims.

In the drawing,

Figure 1 is a perspective view of the crib, with one side, in part, removed, showing the exposed cut ends in section;

Fig. 2 is a side view, in elevation of one of the minor channels;

Fig. 3 is a top view of Fig. 2;

Fig. 4 is an end view thereof;

Fig. 5 is a side view, in elevation of one of the major channels;

Fig. 6 is a top view of Fig. 5;

Fig. 7 is an end view of Fig. 5;

Fig. 8 is an enlarged, sectioned, fragmentary view of the beam and bolt assembly;

Fig. 9 is a fragmentary, corner section, showing the structural cooperation of the beams at their 25 end connections;

Fig. 10 is a sectional view in plan of a modified form of construction;

Fig. 11 is a fragmentary view in elevation of Fig. 10; Fig. 12 is a fragmentary view of one of the beam ends; Fig. 13 is a fragmentary side view in elevation, of a further modified form; Fig. 14 is a fragmentary plan view of Fig. 13; and Fig. 15 is a fragmentary, perspective view of a crib in which the minor beams are omitted.

As shown in one form in Fig. 1, the structure comprises, when assembled, a crib formed of edge connected channel beams, the same being constructed of wide or major beams C, and narrow or minor beams B, these being alternately spaced in one tier, in assembly to one another, so as to leave spaces between one another for soil inspection, tamping and the like, as previously set forth.

As will be noted in Figs. 1, 4, 7, 10, 11 and 12 the beams are formed with double flanges at

their opposite sides 8, one main flange 1 being formed at right angles to the said sides and another smaller flange 2 being formed at right angles to flange 1. These flanges have the plural functions of reinforcing the beams at their edges and to act as keys and where the beams are walled in, or the pit filled with concrete, they act also to bond or key the cement fill or wall into a unitary, permanent construction.

As will be noted in Figs. 3 and 6, the beam flanges 2 are provided with bolt receiving apertures 3 whereby, during erection, the beams B and C may be connected in operative assembly, as shown in Fig. 1. These bolt receiving apertures are so located in both the major and minor beams as to be in registry when erected, so that the threaded joining bolts 4, Fig. 8, may be assembled through the registered apertures 3 to join the flanges 2 of the beams B and C.

In order to maintain the beams in horizontal, spaced assembly, tubular spacers 5, Fig. 8, are provided whereby to hold the major and minor beams apart between the bolt head 7 and threaded nut 6, as shown in Fig. 8.

The relative difference in width of the beams B and C is equal to the length of the spacers 5, Figs. 1 and 8, so that when the assembly is accomplished, as in Fig. 1, the structure will be unitary.

The webs of the major beams C are each provided adjacent their opposite ends with upstanding lugs A, these being blanked out of the webs and bent inwardly and offset at an angle to said webs, as best seen in Fig. 9. These lugs A act as stops for the opposite ends of the minor beams B, when the beams are assembled into a shoring unit, as in Fig. 1, so that the thrust pressure of the earth walls against the ends of the beams B will be amply supported at their ends and said lugs A.

As will be seen in Fig. 1, each tier of construction comprises two major beams C—C located opposite one another on two opposite sides of the assembly, and on the other opposite sides of the same tier are located two minor beams B—B. The next successive tier assembly comprises, as above, two opposed major beams C—C and two opposed minor beams B—B, which are so alternately mounted as to have the major beams C—C in contact at their ends and there operatively held by threaded short bolts 4. Between the alternately spaced and connected beams C—C are located, alternately, a second set of minor beams B—B, these being connected to the major beams C—C of the first tier by the tubular bolt construction shown in Fig. 8.

As thus shown and described, the successive, adjacent tiers of beams comprise juxtaposed major and minor beams alternately assembled to form an open-work crib.

As previously noted, the tiers of shoring elements may be assembled at the bottom of the structure and will follow downwardly as the excavation progresses.

It is intended that where the word "pit" occurs, throughout this application, that any open cut pits or trenches is intended.

In the modified form shown in Figs. 10, 11 and 12, the beams B' and C' are all of one width, and as assembled have no spaces between them.

In this construction, the beams are flanged as described for Figs. 1 to 9, inclusive, and are assembled flange to flange and are locked in unit assembly by bolts, one of which, 4', is shown in Fig. 11, this fastening not requiring spacers, as

the beams are so assembled as to form a rectangular walled, closed, tubular construction.

As in the previous Figs. 1, 5, 6, 7 and 9, one of the coacting beams B' has upstanding, offset pressure lugs, A', Figs. 10 and 11, whereby to sustain the fitted in ends of the coacting beams C'.

The coacting beam C', has its opposite ends cut to remove the flanged sections thereat, and to provide a reduced end E, Fig. 12, whereby said reduced end may be fitted into the flanged ends of the beam B'. As thus constructed, the crib thus formed is box-like, in assembly.

In Figs. 13 and 14, there is shown a form of pit sheeting which is especially adapted for use in open, substantially continuous trench work, where pit sheeting is required only to retain the sides of the cut. In this, the minor beams are dispensed with, and simple flange ended bars or strut forming elements 9 are substituted. The struts 9 may have right angled flanges 10 on their ends, these flanges being preferably bolted by threaded bolts to the beams C', one of such bolts 11 being shown in Fig. 14. As constructed in Figs. 13 and 14, a series of shoring cribs may be constructed in adjoining units and thus form substantially continuous lengths of trench side wall supports.

It will be noted from the foregoing that the beams in the structures shown in Figs. 1 to 8 inclusive, concurrently act as earth retaining elements and also as struts at the end of the adjoining beams.

In Fig. 15 there is shown a fragmented, perspective view of a crib construction in which the channelled beams 13, 13' and 13'' may be all of one width, and these may be of the same general dimensions as either the major or minor beams of Fig. 1, and thus the minor beams, or their equivalent of Fig. 1, are omitted. This construction leaves larger spaces between the associate beam edges, leaving this structure especially adapted for use in excavations which are dug in clayey soil. It has been found that the walls of such excavations are much more self-sustaining than are the walls of pits dug in ordinary soil or loam, or the walls of pits dug in gravelly locations, and thus pits dug in clay strata do not require so much pit sheeting, which, due to the wider spacing of the beams or sheets, is more economical in material and labor to erect. The principles and features involved in the structure of 15 are substantially identical with that of the structure of Fig. 1.

The structure of Fig. 15 comprises a plurality of superposed beams 13, 13' and 13'', preferably of equal width, though beams of unequal width may be used, the beams having edge contacts only at their corners 14, at which contacts they are bolted together by bolts 15. As shown in Fig. 15 a complete tier is formed by alternately opposed beams like 13 and 13', two beams 13' being affixed in superposed corner contact with two opposed lower beams 13, thus to form a single rectangular tier.

The beams 13, 13' and 13'' are provided with registering bolt receiving apertures in their flanges, as described for Fig. 1, and the spaced beams in each side of the crib are connected together by tubular separators 16—16, through which threaded bolts 17 are passed as shown and described for Fig. 8.

In the structure of Fig. 15, each beam 13—13' acts in the double function of a wall retaining pit sheet on its operative side and also as a strut for its adjacent corner connected beam 13. Thus

all beams in this structure act as pit sheets and struts, concurrently.

Having thus described the invention, what is claimed is:

1. A shoring structure assembly comprising a plurality of tiers of beams one above the other, each tier comprising opposite horizontal parallel beams, each beam spaced above and parallel to a beam of a tier below, and substantially perpendicular to opposite beams of the tier next below; each beam comprising an upright web longitudinal to the beam provided with wide flanges turned laterally toward the opposite beam and then inwardly toward each other to form smaller flanges, thus providing a channel opening toward the interior of the assembly, each lower wide flange resting on, and being bolted to, an upper wide flange of the beam next below of the tier next below; and means at least in part filling the space between adjacent parallel beams.

2. A shoring structure assembly comprising a plurality of tiers of beams one above the other, each tier comprising opposite beams, each beam spaced above a beam of a tier below, and transverse to opposite beams of the tier next below; each beam comprising an upright web longitudinal to the beam provided with wide flanges turned laterally toward the opposite beam and then inwardly toward each other to form additional strengthening flanges, thus providing a channel opening toward the interior of the assembly, each lower wide flange resting on, and being bolted to an upper wide flange of the beam next below; and means at least in part filling the space between the spaced beams.

3. A structure as in claim 2 in which said means includes upright bolts connecting said wide flanges with flanges spaced therefrom, and tubular spacers around said bolts and engaging adjacent flanges.

4. A shoring structure assembly comprising a plurality of tiers of beams one above the other, each tier comprising horizontal opposite parallel wide beams and intermediate narrow beams connecting adjacent ends of said wide beams; each wide beam being spaced above a narrow beam of the tier next below, and having its ends resting on ends of wide beams; each wide beam comprising an upright web having wide flanges turned laterally toward the opposite wide beam; an end of each lower wide flange resting on an end of an upper wide flange of the wide beam next below; each narrow beam comprising an upright longitudinal web provided with laterally turned side flanges; the ends of said narrow beams being disposed between said flanges of the wide beams and substantially against the web of the wide beams, with said side flanges engaged with said flanges of the wide beams.

5. A structure as in claim 4 having lugs at the end portion of each wide-beam web having free ends engaged with the inner face of the narrow-beam webs to prevent their movement longitudinally inwardly of the wide beams.

6. In a structure as in claim 4, upright bolts connecting said lower wide flanges with the upper side flanges next beneath; and tubular spacers around said bolts and engaging adjacent flanges.

7. A shoring structure assembly comprising a plurality of tiers of beams one above the other, each tier comprising horizontal opposite parallel wide beams and intermediate narrow beams connecting adjacent ends of said wide beams; each wide beam being spaced above a narrow beam of the tier next below, and having its ends resting

on ends of wide beams; each wide beam comprising an upright web having wide flanges turned laterally toward the opposite wide beam and then inwardly toward each other to form smaller flanges; each lower wide flange resting on, and being bolted to an upper wide flange of the wide beam next below; each narrow beam comprising an upright longitudinal web provided with side flanges turned inwardly of the assembly and then toward each other; the ends of said narrow beams being disposed between said narrow flanges and substantially against the web of the wide beams, with said side flanges engaged with said narrow flanges.

15 8. A shoring structure assembly comprising a plurality of tiers of beams one above the other, each tier comprising horizontal opposite parallel beams and intermediate beams connecting adjacent ends of said opposite beams; each opposite beam being substantially engaged with an intermediate beam of the tier next below, and having its ends resting on ends of said opposite beams respectively of said tier next below; each opposite beam comprising an upright web longitudinal to the beam provided with wide flanges turned laterally toward the opposite wide beam; each lower wide flange resting on an upper wide flange of the tier next below; each intermediate beam comprising an upright longitudinal web provided with side flanges engaging against adjacent wide flanges and turned inwardly of the assembly and then toward each other; said side flanges being cut away at the ends to provide end shoulders, substantially engaged with said flanges of the opposite beams, and web extensions disposed between said flanges of the opposite beams and substantially against the web of said opposite beams.

30 9. A structure as in claim 8 comprising inwardly blanked pressure lugs at the end portion of each web of the opposite beams, said lugs having free ends engaged with the intermediate-beam webs to prevent their movement longitudinally inwardly of said opposite beams.

40 10. A shoring structure assembly comprising a plurality of tiers of beams one above the other, each tier comprising horizontal opposite parallel beams and intermediate beams connecting adjacent ends of said opposite beams; each opposite beam being engaged with an intermediate beam of the tier next below, and having its ends resting on ends of said opposite beams respectively of said tier next below; each opposite beam comprising an upright web longitudinal to the beam provided with wide flanges turned laterally toward the opposite wide beam and then inwardly toward each other to form smaller flanges, thus providing a channel opening toward the interior of the assembly; each lower wide flange resting on, and being bolted to an upper wide flange of the tier next below; each intermediate beam comprising an upright longitudinal web provided with side flanges engaging against adjacent wide flanges and turned inwardly of the assembly and then toward each other; said side flanges being cut away at the ends to provide end shoulders, substantially engaged with said smaller flanges, and web extensions disposed between said smaller flanges and substantially against the web of said opposite beams; inwardly blanked pressure lugs at the end portion of each web of the opposite beams, said lugs having free ends engaged with the intermediate-beam webs to prevent their movement longitudinally inwardly of said opposite beams.

11. A shoring structure assembly comprising a plurality of tiers of beams one above the other, each tier comprising horizontal opposite parallel beams; each beam being spaced above and parallel to a beam two tiers below, and having its ends resting on ends of beams respectively of the tier next below; each beam comprising an upright web longitudinal to the beam provided with wide flanges turned laterally toward the opposite wide beam and then inwardly toward each other to form smaller flanges, thus providing a channel opening toward the interior of the assembly; each lower wide flange resting on, and being bolted to an upper wide flange of the wide beam next below; and strut bars disposed between adjacent ends of opposite beams of the same tier, and having laterally inwardly turned end flanges bolted to the axial portion of the webs of said ends of the beams.

12. A shoring structure assembly comprising a plurality of tiers of beams one above the other, each tier comprising horizontal opposite parallel beams and intermediate beams connecting adjacent ends of said opposite beams; each opposite beam being engaged with a beam of the tier next below, and having its ends resting on ends of the engaged beam of said tier next below; each opposite beam comprising an upright web longitudinal to the beam provided with wide flanges turned laterally toward the opposite wide beam and then inwardly toward each other to form smaller flanges, thus providing a channel opening toward the interior of the assembly; each lower wide flange resting on, and being bolted to an upper wide flange of the tier next below; each intermediate beam comprising an upright longitudinal web provided with side flanges engaging against adjacent flanges of said opposite beams and turned inwardly of the assembly and then toward each other; the ends of said intermediate beams being substantially engaged with and between said narrow flanges of the said opposite beams, and substantially against the webs of said opposite beams; inwardly blanked pressure lugs blanked from the end portions of each web of the opposite beams, said lugs having free ends engaged with the intermediate-beam webs to pre-

vent their movement longitudinally inwardly of said opposite beams.

13. A shoring structure assembly comprising a plurality of tiers of beams one above the other, each tier comprising horizontal opposite parallel wide beams and intermediate narrow members connecting adjacent ends of said wide beams; each wide beam being disposed above a portion of a beam of the tier next below, and having its ends resting on ends of wide beams; each wide beam comprising an upright web having wide flanges turned laterally toward the opposite wide beam and then inwardly toward each other to form smaller flanges; each lower wide flange resting on an upper wide flange of the wide beam next below; each narrow member comprising a longitudinal flat portion of narrow upright cross section; the ends of said narrow members being disposed between said narrow flanges and substantially against the web of the wide beams; means carried by the end portion of each wide-beam web and engaged with the end portion of the narrow member to prevent their movement longitudinally inwardly of the wide beams.

14. A shoring structure assembly comprising a plurality of tiers of beams one above the other, each tier comprising horizontal opposite parallel wide beams and intermediate members connecting adjacent ends of said wide beams; each wide beam being disposed above at least a portion of a beam of the tier next below, and having its ends resting on ends of the engaged wide beams; each wide beam comprising an upright web having wide flanges turned laterally toward the opposite wide beam and then inwardly toward each other to form smaller flanges; each lower wide flange resting on an upper wide flange of the wide beam next below; each intermediate member comprising a longitudinal flat portion of narrow upright cross section; the ends of said intermediate members being disposed between said narrow flanges and substantially against the web of the wide beams; means carried by the end portion of each wide-beam web and engaged with the end portion of the intermediate member to prevent their movement longitudinally inwardly of the wide beams.

JOHN L. WASHBOURNE.
